UNITED STATES PATENT OFFICE.

LÉONCE BLANCHET, OF PARIS, FRANCE, ASSIGNOR TO LA SOCIÉTÉ DE CHIMIE ET A
CATALYSE INDUSTRIELLE SIEGE SOCIAL, OF PARIS, FRANCE.

OIL-GAS APPARATUS.

Application filed August 1, 1921. Serial No. 489,010.

(GRANTED UNDER THE PROVISIONS OF THE ACT OF MARCH 3, 1921, 41 STAT. L., 1313.)

To all whom it may concern:

Be it known that I, LÉONCE BLANCHET, a citizen of the Republic of France, and a resident of Paris, France, have invented certain new and useful Improvements in Oil-Gas Apparatus (for which I have filed applications in France on February 20, 1918, Patent No. 496,539, granted on August 6, 1919, and in England on October 15, 1918; Patent No. 140,128, dated March 25, 1920), of which the following is a specification.

The present invention relates to the production of rich gases and liquid fuel by means of petroleum residues and other hydrocarbon products of low thermal value.

It is known that the use of blue water gas or other gas of low thermal and lighting value is becoming more and more general for heating or lighting; its heating and lighting properties becoming increased by carbureting the gas with hydrocarbon products of low value, such as by-products of petroleum, which are vaporized in such a manner that their almost complete decomposition is effected and their transformation into hydrogen and carbon. This method, however, does not obtain the desired purpose.

The object of the present invention is to increase the calorific and lighting value of blue water gas or other gas of low thermal value; and according to the invention, the vapors of petroleum residues are passed through retorts containing catalyzers heated to between 500 and 600° C. The heavy hydrocarbons split up into vapors and gases consisting of non-condensable olefines and paraffins, light hydrocarbons which distil over up to 150° C., and heavier hydrocarbons. The gases thus formed are mixed with the blue water gas or the like, whereas the liquid hydrocarbons which distil up to 150° C. may be used as fuel for explosion motors. Finally, a very small amount of carbon is deposited on the catalyzers.

The catalyzers used may be metals such as copper or iron, in the form of filings or powder, which are formed into briquettes by means of a binder (gum, glue, starch, and the like).

In the accompanying drawing, Figure 1 represents a diagrammatic vertical sectional

view of a unitary retort embodying the invention, and Fig. 2 is a fragmental horizontal section taken through the catalyzing compartment of the retort.

As shown in said drawing, the retort of the present invention comprises a lower catalyzing portion or compartment A, in the form of a parallelepiped, and an upper vaporizing portion or compartment B; the two portions A and B being made of a single iron casting which is heated by a furnace or other means (not shown). In the interior of the compartment A are arranged channel-iron supports C carrying rows of briquettes D prepared as described above. These briquettes are placed side by side and fill the entire length of the channel-iron supports and the available height of the compartment A. The vaporizer B communicates by means of a pipe connection E with a tank F containing the petroleum residues to be catalyzed, said pipe opening at its inlet end through the bottom wall of tank F and at its outlet end through one of the side walls of the vaporizer at H.

The petroleum residues contained in tank F and fed through pipe E are vaporized in the vaporizer B, which is heated by reason of its direct connection to the catalyzing compartment A whereon it is mounted, both compartments forming parts of the retort, as already stated. The vapors enter the catalyzing compartment A through an opening I and flow through the catalytic mass formed by the briquettes D, contact with which decomposes them into a mixture of light hydrocarbon vapors and gas. This mixture is discharged from the catalyzing compartment A through a pipe G which opens into a suitable condensing coil J, the latter discharging, in turn, into a tank K. The liquid condensates discharged from coil J collect in tank K and the gas, which also passes from said coil into the tank, escapes therefrom through the outlet pipe L, whence it is sent into gas generators in order to be mixed with blue water gas or other gas of low thermal value. The light hydrocarbons obtained by this process as previously described are likewise recovered.

The arrangement described above has the advantage of enabling the catalytic mass to be easily introduced into and withdrawn

from the catalyzing chamber or compartment A for removing the deposited carbon. For this purpose it is sufficient to open the outer door A' of said compartment and to withdraw in succession the several channel-iron supports C with all the briquettes thereon. The catalytic mass can then be easily regenerated.

I claim as my invention:

10. 1. A unitary oil gas retort embodying a lower catalyzing compartment, and a separate upper vaporizing compartment mounted directly upon and directly communicating with the catalyzing compartment; means for supplying liquid hydrocarbon to the vaporizing compartment; and catalyzers disposed in a plurality of removable rows upon the floor of the catalyzing compartment and over which the vapors from
- 15

the vaporizing compartment are caused to pass.

2. A unitary oil gas retort, comprising a catalyzing compartment; a separate vaporizing compartment located upon the top of the catalyzing compartment and directly communicating with the same; a plurality of channel-iron supports disposed within the catalyzing compartment in close parallel relation to one another; and a row of catalyzers arranged in each of said supports, and over which the vapors from the vaporizing compartments are caused to pass, said supports being removable bodily from the catalyzing compartment with the catalyzers in place therein.

In testimony whereof I have signed this specification.

LÉONCE BLANCHET.
